UNITED STATES PATENT OFFICE.

ROBERT B. McGOWAN, OF CINCINNATI, OHIO.

PUMP-GOVERNOR.

1,077,090.

Specification of Letters Patent.

Patented Oct. 28, 1913.

Application filed June 1, 1910. Serial No. 584,464.

To all whom it may concern:

Be it known that I, ROBERT B. McGOWAN, a citizen of the United States, residing at Cincinnati, in the county of Hamilton and State of Ohio, have invented new and useful Improvements in Pump-Governors, of which the following is a specification.

My invention relates to governors for distributing systems of water, gas or air under pressure, and is intended not only to regulate and maintain the proper relation between the pressure or motor speed at the supply side of the system and the pressure at the distributing side in order to properly 10 economize the cost of such maintenance, but also to provide an independent function of safety and economy by shutting off the supply in case of accident, such for example as the bursting of a distributing main, etc.

20 In Patent No. 786,984, granted to me on Apr. 11/05, the mechanism shown was described as attaining the result as an incident of the valve structure in that the valve by continued motion to and beyond the point 25 of its greatest possible opening reached an opposite seat. But besides necessitating a longer valve movement to reach a closure in this direction, the necessity of opening to the full capacity of the admission port, end- 30 tailing possible disaster to the system and mechanism. In a word the closure in such case was not a function of the government of the valve-movement, but of its structure and when beyond control. In my present 35 invention the function of governing, the valve-movement is extended to the condition named, in which the movement of the valve when the normal adjusted limit of opening is reversed and the valve again 40 seated without any opening of the valve port greater than the predetermined limit—whatever might be the greater physical capacity for opening.

The concrete illustration of my invention 45 as shown and described herein, is primarily intended as a governing device for steam pumping systems for raising water, compressing air, etc., where the pump operates directly against and is intended to maintain 50 a predetermined head or pressure which is utilized as a force to control and regulate the admission of steam or other force operating the motor; but it may be used with 55 equal advantage in connection with a reducing valve in a system for the distribution

of air or gas to control the supply according to the demands of use.

To the ends indicated, my invention consists in an improved mechanism for governing the admission of steam or other source 60 of power to the pump-motor, actuated primarily by the pressure of the varying head or resistance at the distributive side of the system, to thus automatically regulate and 65 economically maintain the supply of motor-force within pre-adjusted limits; and in mechanism combined and coöperated therewith to independently control and close the valve when the head or resisting pressure falls below the normal working limit, there- 70 by avoiding useless waste of power and probable damage through over-speeding of the motor.

My invention is equally applicable as applied in connection with a reducing valve, 75 as for example, in low pressure steam-heating systems.

Mechanism for the accomplishment of these objects, with certain improvements in constructive details, is illustrated in the accompanying drawings, in which,—

Figure 1 is a side elevation of my improved safety governor complete;—the throttle valve chamber, the pressure cylinder and parts of the frame, being sectioned 85 to show construction; Fig. 2 is a detail elevation showing the position of the bell cranks and connected parts when the throttle valve is closed through abnormal deficiency of resisting head or pressure in the distribution system; Fig. 3 is a detail showing a modified structure of the cross-heads with provision for easing the seating action of the throttle valve; Fig. 4 is a perspective view of one of the bell cranks, detached; 90 Fig. 5 a detail cross section on the line $x-x$ of Fig. 2; and Fig. 6 a detail, is a perspective of one of the forked controller blocks with its set screws detached.

Referring now to the drawings, 1 designates the throttle valve chamber, containing two valve seats, 2, in the same vertical axis, governed by a double-disk balanced valve 3. Surmounting the valve chamber as a base is a frame 19, which in turn serves 100 as the support of a pressure cylinder, 29, piped to the ultimate distribution tank and receiving pressure according to the head or pressure of water or air, and utilized as 105 the governing force to regulate the opera- 110

tions of the pump. The valve 3, by means of a valve rod, 14, is normally held to its seats by pressure in the cylinder, 29, acting upon a piston, 34, and transmitted through its piston rod, 15, and an intermediate (called herein the upper) cross head, 38, attached to the lower end of the piston rod, and through a second intermediate (called herein the lower) cross-head, 37, attached 10 to the upper end of the valve rod, 14, as will be more fully explained herein.

Operating to uphold the piston, 34, against the head pressure within the cylinder 29, is a coiled spring, 35, in the lower 15 end of the cylinder surrounding the rod 15, bearing upwardly against the piston 34. The spring rests at bottom upon a spring plate, 32, which surmounts an adjustable sleeve, 20, surrounding the piston rod, 15, and threaded through a boss upon the upper 20 end of the frame 19, which constitutes the lower head of the cylinder 29. At its lower projecting end, the sleeve 20 is squared or otherwise fitted for the application of a tool 25 to regulate by its rotation the force of the spring 35; and a set nut 22 upon the sleeve impinges against the lower end of the boss to secure fixity of its adjusted position.

The upper and lower cross-heads are extensions, enlarged in diameter, of the piston rod, 15 and the valve rod, 14, respectively, and are normally in contact, but capable of separation. They are normally held in contact by a spring 36 secured at one end to 30 and coiled around the lower cross head 37, and extending over upon and secured at the other end to the upper cross head 38, in corresponding spiral grooves of the latter, so that the separation of the two is 35 resisted by the tension of the spring 36. To preserve alignment of the cross-heads the upper one, 38, is provided with a lower extension of reduced diameter, seated telescopically, in a corresponding aperture of the lower one, 37, so that while the two cross heads may be separated upon occasion, the guiding contact of one with the other is never lost. The upper cross head 38 is laterally slotted centrally through its 40 mid zone and a pin, 44, is inserted through the slot and its side walls. Through said slot, side by side, from opposite sides, and engaging said pin in common, are inserted the longitudinally slotted ends of the long 45 arms, 39^a, of two bell crank levers, 39, each of which has a fulcrum pivot, 39^c projecting at both of its sides into horizontal guideways 19^b formed in lateral extensions, 19^a, of the frame 19, by which the bell crank is 50 permitted a pivotal movement as well as a lateral travel in the guideway supports. The short arm, 39^b of each bell crank is bifurcated to receive upon pivotal connection a connecting arm 40, the two extending 55 convergently downward into corresponding

pivotal connections with lateral bracket extensions, 37^a of the lower cross head 37. Set screws, 41, terminating in a button, 41^a, are threaded horizontally inward through the ends of the side extensions, 19^a, of the frame 19, bearing against suitable forked controller blocks, 45, the forks of which are fitted to the fulcrum pivots, 39^c, of bell crank 39 to limit their outward travel upon the guides.

The operation of the device as thus constructed is as follows: Steam is admitted by the side inlet 1^a of the valve casing 1, and, as permitted and regulated by the valve 3, passes outward through the bottom exit, 1^b, of the valve chamber, to the steam cylinder of the pump. The spring 35 in the pressure cylinder 29 is adjusted by means of the tension sleeve 20 to allow a sufficient opening of the valve 3 to maintain a predetermined head or pressure in the cylinder 29, under normal conditions of steam pressure. Any increase of resisting pressure in said pressure cylinder 29, above the predetermined limit, which the spring is adjusted to resist, will force the piston rod 15 and its connections and valve 3 downward and correspondingly lessen the flow of steam to the steam cylinder of the pump. Upon decrease of pressure in the pressure cylinder 29, the piston 34 will rise by the tension of the spring 35, elevating the piston rod 15, upper cross head 38, and also (through the tension of the connecting spring 36) elevate the lower cross head 37, valve rod 14 and the valve 3, thus increasing the steam admission to the steam cylinder of the pump;—all in proportion to the decrease of pressure in the pressure cylinder 29. There is thus maintained, under normal conditions, a perfect balance and a uniform head in the distributing tank or system. Now, should the said resisting head or pressure through any accident or other abnormal condition, continue to decrease, notwithstanding the maintenance of maximum steam pressure at the pump, the result without any further provision for steam government, would be overspeeding and injury to the working parts and pipe connections, and, to prevent such results and insure safety, I have provided the other mechanism specified, whose functions are now to be described. Should the pressure in the pressure cylinder 29 continue to decrease, the continued lifting action of the spring 35 elevates the piston rod 15, cross head 38, and also by means of the pin 44, raises the long horizontal arms, 39^a, of bell cranks 39, forcing the fulcrum pivots 39^c outward in their guideways until they contact with their adjustable controller blocks 45. The further continuation of the upward movement of the cross head 38, however, produces a proper pivotal action of the bell crank 130

upon its now stationary fulcrum, and the connecting rods 40 are forced downward, separating the cross heads, moving the lower cross head 37 downward against the tension of the spring 36, carrying the governing valve 3 to its seat and shutting down the pump action. Thus the governor as a whole possesses the function not only of a regulator of the ordinary working action of the pump under normal conditions, but, in addition thereto, of a safety device in case of abnormal conditions, such as breaking of pipe connections, etc.

Since the speed at which the pump operates is directly related to the consumption in the distribution system, the proper governing of its action under normal conditions described, results in economy of steam; and the further regulation under abnormal conditions, reducing the outward pressure, not only prevents useless waste of steam, but insures against disaster. Should the stoppage be temporary, and the normal pressure within working limits, resumed within the system, the action of the pump will be automatically resumed; otherwise steam may be admitted by the by-pass valve 10, and continued until the required working pressure is reached, at which point the device resumes automatic control.

In Fig. 3, I have shown a slight modification of the mode of connecting the so-called cross heads which is intended to ease the seating of the throttle valve and prevent injury thereto. The lower cross head 37 is counterbored, leaving a lower head through which the valve rod 14 enters, and is held by a cap or head 14^a at the upper end of the same. Coiled within the counterbore and seated upon said head 14^a of the valve rod is a spring 42 which is held in compression by an adjustable threaded plug 43, forming the lower guide for cross head 38. These changes of structure effect no change of operation excepting that the valve 3 in any downward movement, will seat without undue stress by weight of parts above, and also the adjustment of the downward moving parts need not be so exact, but the limit of movement may be in excess of that required to seat the valve 3 and thus insure its proper seating when required.

I claim as my invention, and desire to secure by Letters Patent of the United States:—

55

1. In a system of fluid distribution of the character indicated, in combination with a governing valve for regulating the motor force at the supply side of the system, and with mechanism for operating said valve to adjusted working limits less than the valve capacity by means of the varying head or pressure at the delivery side of the system, of auxiliary mechanism connected therewith adapted to reverse the direction of valve 65 operation and close the valve when the decrease of resisting head or pressure passes the normal working limit as adjusted.

2. In a system of fluid-distribution of the character indicated, the combination of a piston under continuous pressure of resistance at the delivery-side, acting in one direction of the piston-movement, and continuous spring-pressure acting in the other direction, a regulating throttle-valve governing the supply of motor force at the supply-side of the system; mechanism connecting said piston and said valve in simultaneous coördinate operation between normal limits of the resisting head or pressure; and mechanism operated by said piston when the resisting pressure decreases below the normal limit to move the valve oppositely to the piston-movement and seat the valve.

75

3. In pump-governing apparatus, the combination of a governing piston actuated in one direction by the head or pressure of fluid supplied by said pump, and in the opposite direction by spring-pressure adjusted to a normal maximum pressure of said fluid, 80 a throttle-valve actuated correspondingly within predetermined limits, and a divided connecting rod, normally connected as one, uniting the valve and piston, but adapted to separate and allow the throttle valve to 95 be closed when the governing pressure falls below the proper limit.

In testimony whereof I have hereunto set my hand in presence of two subscribing witnesses.
